HUMIDIFYING EQUIPMENT FOR MEDICAL USE

James R. Grosholz, Wayne, Pa., assignor to Air-Shields, Inc., Bucks County, Pa., a corporation of Delaware

Application October 18, 1954, Serial No. 462,687

4 Claims. (Cl. 261—78)

This invention relates to humidifying apparatus used for supplying conditioned breathing gas for invalids such as those recovering from sickness or having respiratory ailments.

There are many circumstances under which it is desirable or essential that humidified air be supplied to invalids. It is customary to use for this purpose an enclosure which covers the head and upper portion of the body. Complicated and cumbersome apparatus is used to supply the conditioned gas to the enclosure. Such tent equipment often creates a detrimental psychological effect by producing a feeling of being shut off from normal surroundings and in some instances producing a sensation of dread. Also cooling is required where an enclosure is used.

It is a primary object of the present invention to provide apparatus for supplying humidified air to a patient without the need for an enclosing tent. At the same time the apparatus presents a greatly simplified appearance and its operation and adjustment may be seen and easily understood by the patient, thereby eliminating a possible source of distrust which might cause distress.

Another object of the invention is the provision of readily portable apparatus of this nature which incorporates a gas delivery unit which may be easily adjusted in any direction so that it can be positioned properly close to the patient's nose and mouth.

A further object of the invention is to provide a gas delivery unit which also incorporates the water or medicament being used for humidifying purposes as well as the vaporizing device used for producing the humidification and mixing it with the gas supply.

An important object is to provide improved apparatus for generating and controlling the humidity, particularly with respect to the separation of larger water particles and the mixing of the fine particles with the air being delivered. Improved control of flow is also included in this object.

A still further object is to provide apparatus for operation by the pump unit of the humidifying system which is capable of use as a catheter.

How the foregoing and other objects and advantages are attained will be understood from the drawings, in which—

Figure 1 is a side elevational view showing humidifying apparatus according to the present invention.

Figure 2 is a plan view of the generating and delivery unit to an enlarged scale.

Figure 3 is a sectional view taken in the direction of arrows 3—3, Figure 2.

Figure 4 is a sectional view of the supporting block taken in the direction of arrows 4—4, Figure 3.

Figure 5 is a sectional view taken in the direction of arrows 5—5, Figure 1, showing the air controls and the connections for catheter use.

Figure 6 is a sectional view in the direction of arrows 6—6, Figure 7, showing the swivel mounting with its passages.

2

Figure 7 is a sectional view in the direction of arrows 7—7, Figure 6, showing the air passage from the swivel mounting.

Figure 8 is a sectional view through the upper pivot as indicated by arrows 8—8, Figure 6.

Figure 1 shows a general arrangement of apparatus illustrating the present invention. A small platform 11 equipped with casters 12 supports a vertical post 13. An electric motor 14 operates air compressor 15 which is equipped with intake or suction line 16 and pressure line 17. Oil trap 18 prevents oil particles from entering the delivered air.

Near the upper end of post 13 a shelf 19 supports a container 20 for holding a supply of distilled water. Shelf 19 also supports the reservoir 21 and trap 22 which will be described in detail later.

The air line 17 connects into a horizontal rigid pipe 23 supported on post 13. Pipe 23 supports an air pressure gage 24. At the upper end of post 13 a support member 25 is mounted for rotational movement with respect to post 13. Attached to support 25 by means of pivots 26 and 27 are two parallel supporting rods 28 and 29. At one end of rods 28 and 29 is mounted a supporting block 30 by means of pivots 31 and 32 and at the other end of rods 28 and 29 there is mounted a counterweight 33 having pivots 34 and 35.

Block 30 supports the delivery unit generally indicated by numeral 36, the construction of which is more clearly shown in Figures 2, 3 and 4. Horizontal duct 37 is supported on block 30 and extends to support central post 38 and the upper chamber 39. At the lower end of post 38 is supported reservoir 40, a thumbscrew 41 being used to retain it in position while permitting its removal for cleaning purposes. Between chamber 39 and reservoir 40 the delivery nozzle 42 is supported in a fashion which permits its rotation above the axis of post 38 to provide position adjustment. It will be noted in Figure 2 that nozzle 42 expands in plan view to the delivery end which is provided with a curved outlet as indicated at 43. A shallow dam or wall 44 is provided near the end of nozzle 42 to prevent any condensed moisture from dripping out of the nozzle. Drain holes 45 permit return of condensation to the reservoir 40.

A drip pan 46 is located below the chamber 39 and catches condensed moisture from the chamber walls. Drain hole 47 provides for return of moisture to the reservoir 40. Filler pipe 40a connects to reservoir 40 which is preferably transparent so that the water level indicated at 40b may be readily checked.

Mounted in block 30 is the atomizer unit 48 which may be screwed into place by means of threads 49. Unit 48 is equipped with an air nozzle 50 and a second nozzle 51 connected to the reservoir. Nozzle 51 terminates close to the end of air nozzle 50 in position so that the air flow induces a suction action to draw a supply of water into the air stream in the form of fine particles. The water is delivered to nozzle 51 by means of channel 52 in block 30 which connects by means of tubes 53 and 53a to the screened inlet 54 in the reservoir 40. Air is delivered to nozzle 50 through channel 55 in block 30.

To increase the volume of flow through the delivery unit 36 outside air is admitted to the pipe 37 through the slot 56. The suction induced by flow of air from the atomizer causes the inflow of air through slot 56. The volume is controlled by means of collar 57 which is supported on thread 58 so that rotation of collar 57 varies the degree of effective opening of slot 56.

Figure 4 illustrates the pivotal mounting of block 30 and the manner in which the air is delivered through the pivot to the block. Here it will be seen that the upper parallel rod 28 is attached to block 30 by means of bolt 31 and nut member 59, a nylon bushing 60 being pro-

vided to give smooth frictional restraint so that the unit will remain in any position to which it is adjusted. The lower supporting rod 29 is attached by a short bolt 32 which extends into a cylindrical member 62 in which is provided an air passage 63. Passage 63 leads to an annular groove 64 which connects to the channel 55 in block 30. Suitable seals as indicated at 61 are provided in member 62. One end of member 62 projects outside of block 30 and is attached to pipe 65.

Figures 5 to 8 inclusive show the mounting and connections at the upper end of post 13. Here it will be seen that connecting pipe 65 is attached to the end of cylindrical pivot member 66 while rod 29 is supported by bolt 27 to pivot member 66 which in turn is mounted in support 25. Figure 8 shows how upper rod 28 is attached to the support 25 by bolt 26.

Figures 5 and 6 show the upper end of post 13 with internal annular sleeve 67 to the top of which is attached plate 68. A rotatable axle 69 is supported in sleeve 67 by thrust bearing 70 which is supported on plate 68 and in housing 71. Axle 69 is attached to support 25 by threaded terminal 72. The air connection thus passes through pivot 66 to central channel 73 in axle 69 and then through hole 74 to annular groove 75 which in turn connects to delivery pipe 23 from the compressor (see Figure 5). Seals 76 are provided at each side of groove 75.

In Figures 6 and 7 it will be seen that a pin 77 is fastened to housing 71 and two stop pins 78 and 79 are mounted in plate 68. These pins limit the angular swing of the support 25. In addition a thumbscrew 80 is provided to lock the axle 69 at any desired position of adjustment. It will also be noted in Figure 7 that plate 68 is provided with slots 81 and 82 to allow entry of bar 29 and pipe 65 respectively. These slots serve to permit lowering the delivery unit 36 to the position 36a shown in dotted outline in Figure 1. Slots 81 and 82 retain the unit in central lowered position over the platform 11 for storage purposes.

In Figure 5 a small needle valve 83 is shown at the end of air delivery pipe 23. This valve 83 allows bleeding of air from the delivery line thereby providing for control of the air supply to the atomizer to produce the desired amount of mist.

Also in Figure 5 the catheter system attached to the suction side of the pump is shown. The suction line 16 connects to the support 84 which has a chamber 85 to one end of which is connected the bleed valve 86. By opening or closing valve 86 the amount of suction in the catheter system is controlled. Connected to suction chamber 85 is a tube 87 which leads to trap 22. Another tube 88 leads from the bottom of trap 22 to the top of catheter chamber 21. The catheter tube 89 is attached to the top of chamber 21 and this tube 89 is used for the removal of secretions which are deposited in chamber 21. When the catheter is used the air line 17 may be removed from the pump and when the humidifier is in use the suction line 16 may be removed.

The operation of the apparatus is relatively simple. When used to provide humidified air for a patient the apparatus may be conveniently moved to the bedside and if desired the major part of the platform 11 with the motor and compressor may be located under the bed in order to further reduce the effective space used by the apparatus. With the reservoir 40 supplied with water and with suction tube 16 removed and delivery tube 17 connected, the compressor is placed in operation by starting the motor 14 (electrical connections not shown). The degree of humidity and volume delivered is then adjusted to the desired condition by operation of the bleeder valve 83 and the air control collar 57. Valve 83 controls the pressure delivered to the atomizer unit, the pressure being reduced by opening valve 83 and bleeding off part of the air. With reduced pressure less water mist is produced by the atomizer. By rotating the collar 57 to open

the air inlet slot 56 increased volume of air is admitted. The vacuum inherent in tube 37 by virtue of the airflow induced by the atomizer jet provides for inflow of outside air through tube 37 which is mixed with the air and mist from the atomizer. Removal of larger mist particles takes place as the air flows through tube 37, then through mixing chamber 39 where the flow velocity carries such larger water particles against the wall where they adhere and flow back to the reservoir.

10 Thus the delivered air contains only very fine mist which is not wetting. The adjustments provide for full control of volume and concentration. The delivery nozzle 42 may be adjusted to the desired position close to the patient's face by raising or lowering on the parallel 15 rod linkage, the upper position of adjustment being indicated at 36b. In addition the apparatus may be swung in a horizontal direction on its mounting axle 69 and the nozzle 42 may be rotated to the most effective delivery position.

20 For use as a catheter, pressure tube 17 may be disconnected and suction tube 16 attached to the pump 15. The desired degree of suction is obtained by adjusting the bleeder valve 86. Opening valve 86 admits air to tube 16 and thus reduces the suction action in the connecting tubes 87 and 88 to jar 21. The catheter to be used is connected to flexible tube 89 and the fluids drawn off are carried through tube 89 to the container or jar 21 which may be emptied after use.

From the foregoing it will be evident that I have provided an improved form of apparatus for medical use, particularly in connection with the generation and delivery of humidified air for breathing. This apparatus gives a convenient means of inhaling finely suspended water particles without the necessity of an enclosing canopy. 35 A large volume of mist may be generated and delivered to the region of the patient's face to supply a cloud which continually replenishes itself. The controls permit accurate adjustment of the degree of localized mist concentration. The universal position adjustment allows

40 the delivery nozzle to be located so that the mist cloud envelopes the face in a satisfactory manner. The construction further permits ready removal of the reservoir and the atomizer unit for inspection and cleaning. By means of the slotted plate at the top of the pedestal the linkage may be held in retracted central position for storage. The auxiliary use of the pump to operate a catheter unit further extends the usefulness of the apparatus.

I claim:

1. Apparatus for producing humidified air including a 50 duct, an atomizer unit positioned at one end of said duct with its ejection direction parallel to the axis of said duct, the end of said duct opposite said atomizer unit being open and supported in a chamber of relatively 55 larger sectional area than said duct, said chamber being closed at its upper side and open at its bottom side to provide downward delivery of the gas therefrom, the outlet end of said duct being located generally centrally in said chamber, a final delivery channel extending horizontally from the open bottom side of said chamber, a fluid container located directly below said chamber at an elevation lower than said delivery channel and cooperating with said delivery channel to otherwise close the bottom side of said chamber, and a support connected to said container and extending upwardly to engage said duct.

2. Apparatus for producing humidified air including a 60 duct, an atomizer unit positioned at one end of said duct with its ejection direction parallel to the axis of said duct, the end of said duct opposite said atomizer unit being supported in a chamber of relatively larger 65 sectional area than said duct, said chamber being closed at its upper side and open at its bottom side to provide downward delivery of the gas therefrom, the outlet end of said duct being located generally centrally in said

chamber, a final delivery channel extending horizontally from the open bottom side of said chamber, a fluid container located directly below said chamber at an elevation lower than said delivery channel and cooperating with said delivery channel to otherwise close the bottom side of said chamber, and a support connected to said container and extending upwardly to engage said duct, said duct being mounted horizontally at an elevation higher than said delivery channel and a fluid delivery pipe extending from said container to said atomizer unit.

3. Apparatus for producing humidified air including a duct, an atomizer unit positioned at one end of said duct with its ejection direction parallel to the axis of said duct, the end of said duct opposite said atomizer unit being supported in a chamber of relatively larger sectional area than said duct, said chamber being closed at its upper side and open at its bottom side to provide downward delivery of the gas therefrom, the outlet end of said duct being located generally centrally in said chamber, a final delivery channel extending horizontally from the lower side of said chamber, a supporting member connected to said duct, a post structure, a pair of parallel links pivoted to said member and extending to the upper end of said post structure, a pivotal connection between said links and said post structure, thereby providing vertical adjustment of said delivery channel, said delivery channel being rotatable with respect to said supporting member about a vertical axis, thereby providing directional adjustment of said channel, one of said links being in the form of a tube which serves as a channel for delivery of gas to said atomizer.

4. Apparatus for producing humidified air including a duct, an atomizer unit positioned at one end of said duct with its ejection direction parallel to the axis of said duct, the end of said duct opposite said atomizer unit being supported in a chamber of relatively larger

sectional area than said duct, said chamber being closed at its upper side and open at its bottom side to provide downward delivery of the gas therefrom, the outlet end of said duct being located generally centrally in said chamber, a final delivery channel extending horizontally from the lower side of said chamber, a supporting member connected to said duct, a post structure, a pair of parallel links pivoted to said member and extending to the upper end of said post structure, a pivotal connection between said links and said post structure, thereby providing vertical adjustment of said delivery channel, said delivery channel being rotatable with respect to said supporting member about a vertical axis, thereby providing directional adjustment of said channel, one of said links being in the form of a tube which serves as a channel for delivery of gas to said atomizer, one of said links extending beyond said post structure and having a counterweight attached thereto.
